(57) CLAIM

The ornamental design for a reverse bucket for a personal watercraft, as shown and described.

DESCRIPTION

FIG. 1 is a front view of a reverse bucket for a personal watercraft, according to one embodiment of the present invention.

FIG. 2 is a rear view of the reverse bucket of FIG. 1.

FIG. 3 is a top view of the reverse bucket of FIG. 1.

FIG. 4 is a bottom view of the reverse bucket of FIG. 1.

FIG. 5 is a left side view of the reverse bucket of FIG. 1. The right side view is symmetrical to the left side view, and is shown in FIGS. 10-11, installed on a personal watercraft.

FIG. 6 is a cross-sectional view of the reverse bucket, taken along line 6—6 of FIG. 1.

FIG. 7 is a cross-sectional view of the reverse bucket, taken along line 7—7 of FIG. 5.

FIG. 8 is a cross-sectional view of the reverse bucket, taken along line 8—8 of FIG. 5.

FIG. 9 is a perspective view of the reverse bucket of FIG. 1, from an upper left rear side perspective.

FIG. 10 is a reduced scale, environmental view of the reverse bucket of FIG. 1; and,

FIG. 11 is an enlarged, right side view of the reverse bucket of FIG. 1.

The dot-dash broken lines show a lowered configuration of the reverse bucket, and the remaining broken lines show environment. The broken lines form no part of the claimed design.
